UNITED STATES PATENT OFFICE.

WILLIAM E. PARSONS, JR., OF NEW YORK, N. Y.

DESIGN FOR A CIGAR-COUNTER UTENSIL.

SPECIFICATION forming part of Design No. 29,971, dated January 10, 1899.

Application filed November 17, 1898. Serial No. 696,726. Term of patent 14 years.

To all whom it may concern:

Be it known that I, WILLIAM E. PARSONS, Jr., of the city of New York, borough of Manhattan, in the county and State of New York, have invented and produced a new and original Design for a Cigar-Counter Utensil, of which the following is a full, clear, and exact description.

Reference is to be had to the accompanying drawing, forming a part of this specification, in which the figure is a perspective view of a cigar-counter utensil, showing my design.

My design in its entirety consists of an ornamental base A, on which appears a post or staff B, having a display or advertising shield C appearing at the upper end of the post and

bearing the representation of a box of cigars, the post B appearing at the rear of a globe-lamp D, rising from the base and flanked by tubular posts E, having ornamental caps E', and a box F appearing between the posts on the narrowed front end of the base.

The leading features of my design consist of a base, a staff having a display-shield, a globe-lamp, and a box.

I claim—

The design for a cigar-counter utensil, herein shown and described.

WILLIAM E. PARSONS, JR.
